Application August 20, 1957, Serial No. 679,290

4 Claims. (Cl. 179—111)

This invention relates to methods of and means for generating sound. The invention is based on the discovery that a pair of inexpensive, single-ended, electrostatic loudspeakers can be mounted and driven so as to form a system which achieves acoustic performance at least equal to that of a double-ended speaker and greatly superior to that provided by the same single-ended speakers when they are arranged in conventional ways. The invention uses a system of single-ended speakers in oppositely facing, closely coupled, push-pull driven arrangement, which not only allows the use of a readily constructed, simply operated structure but also obtains an unusually high degree of fidelity, and fully maintains the same for an unusually long period of time.

Thus it is a basic object of the invention to provide highly accurate acoustic reproduction of electrical signals by simple and rugged means. Another object is to avoid the conventional but difficult clamping of a vibratory membrane between a pair of backplates and thereby to reduce the cost of the speaker, as well as the deleterious effects of atmospheric changes, aging of materials and the like. The new unit accordingly uses a system of speaker sections each of which has only one backplate, a membrane section thereon, and simple but effective tensioning apparatus for the membrane. An important object is so to orient, couple and drive said membrane sections as to eliminate undesirable second and higher harmonics of the driving frequencies. Additional objects may be noted from the description which follows.

In connection with the description, reference will be made to the drawing appended hereto, wherein Figure 1 is a perspective view of a simple embodiment of the new speaker, while Figure 2 is a slightly enlarged section taken along line 2—2 in Figure 1 and Figure 3 is an additionally enlarged, fragmentary view of a marginal detail from Figure 2.

Figure 4 is an exploded illustration of the apparatus of Figure 1, on the approximate scale of Figure 2.

Figure 5 is a greatly enlarged, schematic view showing details of a speaker generally similar to that of Figures 1 to 4. Figures 6-A, B, C and D are diagrams of functions of parts of such a speaker.

Figures 7 and 8 show slightly modified speakers, in views generally similar to Figure 2.

Referring first to Figures 1 and 2, the new sound reproducer comprises two electrostatic speakers 10 and 11, facing in directions opposite one another, the two speakers being shown as having identical shapes and symmetrical arrangement. Each portion 10 and 11, by itself, may constitute a complete single-ended, electrostatic speaker, when such a speaker is considered as comprising a vibratory membrane, tensioned over a backplate.

Preferably, although not necessarily, each individual speaker 10 and 11 comprises, as shown, a sleeve-like membrane 12 encircling a rigid frame 13, and each frame has a slightly curved backplate 14 inserted therein and retained in place by the membrane 12 which is tensioned

2

over the same. The convex sides of the two backplates, with the membranes thereon, are shown for illustrative purposes as facing one another. According to an important feature of the invention the membranes are spaced apart by certain limited distances, as will be explained hereinafter.

Each backplate 14 has the approximate shape of a relatively flat, cylindrical segment over which the sleeve-like membrane 12 can be stretched by simple unidirectional tension. As further shown in Figure 3, each frame 13 has one of the curved backplates 14 countersunk into grooves 15 in the surface 14' of the frame so that the exposed surfaces of the frame and of the backplate are flush with one another. The frames may be molded of plastic, whereas the backplates 14 may be made of perforated sheet metal, having many small openings 16 therein. The openings should be slightly larger in diameter than the plate is thick.

In order to allow substantial vibration of the membrane 12 on the stationary backplate 14, spacer members are provided. One embodiment of such members is illustrated in Figure 3 as comprising a series of thread or wire sections 17, extending over the exposed surface of the plate in directions parallel to the axis of the curved plate 14. Ends 18 of such threads (Figure 4) can be anchored, for instance on the plate 14, by known fastening means, not shown. Various equivalents of such threads are known; for instance Figure 5 illustrates spacers 17A integral with the backplate 14.

The tensioning of each membrane sleeve 12 over the corresponding series of spacers is preferably achieved by a mechanism 19 (Figures 1 and 2) of the type described in the copending application Serial No. 425,607, filed by the present inventor on April 26, 1954, Patent No. 2,824,178, and entitled "Transducers," which is assigned to the assignee of the present invention. This mechanism will therefore be described but briefly. Opposite the concave side of each backplate 14 and in contact with the sleeve 12 there is provided a pressure bar 20, extending parallel to the axis of curvature of the plate. Springs 21 resiliently react against the bar 20, and thereby against the membrane 12, to tension the latter over the frame 13 and backplate 14.

Each bar 20 may serve also as a means for electrically connecting a conductive layer 12' on the insulating membrane 12 (schematically shown in Figure 5) to a terminal 22 (Figure 1), whereas each plate 14 has another terminal 22 connected thereto. The entire speaker, accordingly, may have four terminals, and each membrane can be biased and driven independently, in suitable cooperation with the other membrane.

According to the invention it is important to provide a certain spacing between the two units 10, 11. The required dimensions will be explained hereinafter, in connection with the operation of the device, but it may here be noted that, in order to assure the proper spacing, each frame 13 has two spacing members or bosses 23, one at each end thereof (Figures 1 and 2). These bosses are desirably removable from the frames 13, in order to simplify installation of the sleeve-shaped membranes 12. Fastening means such as screws 24 are employed to secure bosses 23 to one another and to the frames 13, in suitably abutting relation. The preferred spacing of the units 10, 11, provided in this way, is such as to maintain, between the membranes 12, a thin air cushion A (Figures 2, 4, 5).

The manufacture of the new apparatus 10, 11, is very simple. The frames 13 and bosses 23 can be formed of suitable, dimensionally stable plastics, by well known molding operations. The backplates 14 can be cut from suitable sheet material, such as perforated aluminum plate,

which has a slight cylindrical curvature incorporated therein and to which the spacers 17 are suitably attached. Slight irregularities may be present in the plate surface, but, as a practical matter, adequate tensioning of the vibratory membrane 12 can be established when the plate 14 is curved, for instance if it has a rise of $\frac{1}{16}$ inch in an arc of 3 or 4 inches length. The membrane sleeves 12 can be made of thin, strong, insulating sheet material such as that known as "Mylar," a type A polyester manufactured by E. I. du Pont de Nemours and Co., with a suitable conductive coating 12' thereon.

Desirably, and according to known principles, the thickness of the coating 12' amounts only to a small fraction of a mil; that of the entire membrane 12 amounts to a larger fraction of a mil; and the thickness of the flat air space B (Figures 3 and 5), which is maintained by the spacers 17 or 17', between the membrane 12 and the backing 14, is of the order of not more than a very few mils, to maintain high electro-acoustic sensitivity.

Referring finally to the dimensions of air cushion A, or of any differently shaped space between the membrane sections 12, 12A (Figure 5): as indicated above, such dimensions are important and even critical, because of the necessity of controlling disturbing harmonics, in a speaker system which shall achieve the results and advantages of the present invention. It has been found to be necessary to limit that dimension of said space which is measured between the membranes 12, 12A, to a value which is generally smaller than the wavelength of the harmonics to be suppressed.

It may be noted that due to the curvature of the single-ended, oppositely arranged speakers shown in the drawing, said dimension or distance varies to some extent, depending on the exact point of a membrane area from which point the said distance is measured. This variation is only of secondary importance for the present invention. The point of major importance is that the distances across the air cushion, gap or space should be smaller, over at least a major part of the membrane areas, than the shortest wavelengths of the audible harmonics to be suppressed.

If the speaker system serves to reproduce both music and speech, the significant harmonics, in this sense, may range up to about 15,000 to 20,000 cycles per second, corresponding to fundamentals of up to about 7,500 to 10,000 cycles. The wavelengths of the fundamentals are in the range of about .6 to .9 inch and those of their second harmonics are less than about .3 to .45 inch. For this reason it will usually be found that the advantages of the present invention are achieved if the width of the air space between membranes 12, 12A, over a major portion of membrane areas, is less than about .3 to .45 inch; at any rate, less than about a half inch.

Each single-ended speaker 10, 11, as shown in the drawing, is desirably curved to form an approximately cylindrical segment. As a result of this curvature, and in view of the preferred, mutually facing arrangement of the curved speakers 10, 11 (Figures 2, 5), the system as shown has lines of minimum distance between membrane areas 12, 12A, parallel to lines of maximum distance therebetween and these latter lines extend along the side edges of the system. It is clear that the minimum distances, in a system as shown, are substantially smaller than either the marginal or the average distances between the areas. These minimum distances may be limited to any suitable, small value, for instance to about five or ten mils, in order to facilitate the construction of the speaker.

In operation, both sections or speakers 10 and 11 have polarizing voltages applied thereto, in order to hold each membrane section 12A', 12A'', etc. (Figure 4) under suitable tensioning for proper vibration, each of these sections being biased towards the corresponding backplate 14, as is known and usual in other signal-ended speakers. For this purpose a source 25 of biasing voltages (Figure 1) is connected with suitable terminals 22, for instance as

shown, with those of the backplates 14, by conductors 22'. As the two speakers face in opposite directions, the polarizing forces bias the two membranes in opposite directions, relative to the air cushion A.

Signal voltages, in push-pull, are provided by the transformer 25' forming part of the output circuit of a suitable signal amplifier, and are superimposed on the polarizing voltages by leads 22" connected for instance, as shown, to the conductive membranes (Figures 1 and 5). The electrical signals and their driving effects are schematically illustrated in Figures 6-A to 6-D. Particularly, the curves S, S-1 (Figures 6-A and 6-D) show respectively the ways in which voltages rise and fall between the membranes of sections 10, 11 on the one hand and their respective backing plates, on the other, as each membrane moves from one of its positions (full lines in Figure 5, points X, X-1 in Figures 6-A, 6-D) to another (broken lines in Figure 5, points Y, Y-1 in Figures 6-A, 6-D), and then back to the original position (full lines in Figure 5, points Z, Z-1 on the curves). Sound is emitted both forwardly and rearwardly (upwardly and downwardly in Figure 5), and of course, suitable, well-known procedures of reflection and/or absorption may be used to utilize and direct the sound, as may be required. The present invention is concerned with the quality rather than with the direction of sound, produced by the system of single-ended speakers. In this connection the following may be noted.

Each individual, single-ended speaker 10 or 11 could be used by itself or both could be used in arrangements different from those according to the present invention. In such cases, however, undesired "even harmonics" of the signal frequencies, including strong second harmonics thereof, would occur in the acoustic vibration generated by the electrostatic signal, because of the super-position 35 of the signal S or S-1 on the polarizing voltage P or P-1. In other words, the individual speaker would generate a distorted acoustic output curve D or D-1 (Figures 6-B, 6-C), having non-linear response to the signal curve S, S-1. The second harmonics H, H-1 would be among the 40 disturbing influences, superimposed over linear acoustic response curves L, L-1. While this has been known for a long time, I believe the present system is the first arrangement of single-ended, electrostatic speakers which eliminates the disturbance in an effective and economical 45 way.

Prior attempts to eliminate the disturbance, in single-ended speakers, were based on the use of a very large and correspondingly expensive speaker unit. This was based on the fact that the distortion was particularly 50 strong when the ratio of signal voltage to polarizing voltage was relatively high. Such ratios were heretofore made as very low, for instance such as 1:10. For this reason all prior, single-ended speakers, and mainly those used for reproducing frequencies extending into a relatively low 55 range, had to be relatively large and expensive.

In the operation of the present speaker unit, by contrast, the thin air cushion A, between two speakers 10 and 11 driven in push-pull, serves as a close acoustic coupling medium, which on the one hand causes the 60 separately driven speakers 10 and 11 to vibrate in unison, in direct response to the signal voltages, while on the other hand cancelling the disturbing even harmonics. From an inspection of Figures 5 and 6-A to 6-D it will be clear that this unique effect is entirely 65 due to the close acoustic coupling A between the single-endedly constructed, double-endedly arranged and operated speakers 10 and 11. For instance, as the electrostatic attraction of the membrane 12-A increases from level X toward level Y, tending to produce the first part of non-linear acoustic response D, the simultaneous decrease of electrostatic force, from X-1, to Y-1, precisely by tending to produce another disturbed acoustic reaction D-1—the two disturbances being equivalent to harmonics H and H-1 in opposite phase—cancels the 70

first-mentioned disturbance, so that two linear responses L, L-1 result.

The net effect is that the two membranes, although simply and cheaply constructed as single-ended units and tensioned with the aid of biasing voltages P, P-1, act in the precise way of a most accurately arranged, mechanically tensioned, double-ended unit, the cost of which would be many times greater and the life expectancy of which would be substantially shorter than that of the present pair of speakers. Even more favorable is the comparison of this present pair of speakers with prior systems of single-ended speakers. Those systems, as noted above, had to utilize a low ratio of signal voltage to polarizing voltage and a correspondingly large membrane area, and they were still unable to fully eliminate the harmonics.

In the present speaker unit, by contrast, the strength of the signals, relative to the polarizing voltages P, P-1, can be and desirably is kept rather high. For instance, the polarizing voltage may be maintained at a level such as 300 volts and the signal voltage curve, as such, may then have peak amplitude such as 100 volts or more, causing signal oscillations between the limits of 250 and 350 volts. Correspondingly the present speaker unit can be made relatively small, even when used to reproduce frequencies which extend from the high range, conventionally supplied by electrostatic "tweeters," to a substantially lower frequency range, such for instance as 1000 or 500 cycles per second.

The greatest fidelity in the production of music, along with an extremely wide range of sound volumes, is obtained by the present speaker if the width of the major portion of the air space A between one membrane section 12A, and the other, 12B, is substantially smaller than the wavelengths of the higher acoustic frequencies to be reproduced. For instance, this space may sometimes be made smaller than one-quarter of the wavelength of the highest fundamental note to be reproduced.

This is readily achieved. As explained above, the desirable spacing, along the lateral margins of the membranes, may amount to a few hundred mils, and the spacing along the center lines of the membranes, as shown, may equal about five or ten mils. Such distances can be established with ease and they can be maintained for a practically indefinite period of time by spacers 23 and frames 13.

The fidelity achieved by these expedients is greatly superior to that of the best, conventional, single-ended speakers. Those latter speakers can, at best, reduce the even harmonics somewhat, and that only if the ratio of signal voltage to biasing voltage is made small and the speaker correspondingly large, expensive and cumbersome.

Double-ended speakers of conventional design, either large or small, have heretofore provided a fidelity which initially was comparable to that maintained by the present system, but this was possible only at much higher cost. In addition, the fidelity once established is retained much more safely and over a much longer period of time by the present speaker unit than by conventional double-ended units. This applies even in case of sharp variations of temperature or humidity, aging of plastic frames, and similar factors. Each section or system 10, 11, employing the membranes, tensioning and connecting parts 12, 13, 14, 19 as explained in said copending application, retains substantially uniform spacing B between membrane 12 and backplate 14, regardless of said variations. This is true even in the event that the surface of the metal from which the plate 14 is formed has irregularities therein. In conventional double-ended speakers, such retention of fidelity has been lacking, even if extreme care was used in originally producing a highly regular backplate surface.

The speaker of Figures 1 to 5 can be modified in many respects, so long as the paired, single-ended speak-

ers are mounted to face in opposite directions, with close acoustic coupling between them and with suitable push-pull drive. For instance, Figures 7 and 8 show modified tensioning devices, either refining the system 5 19 further (Figure 7) by interposing a suitably perforated pressure spreading plate 40 between the spring 21 and membrane 12, to apply pressure to the membrane in a less concentrated way, or on the other hand simplifying the system 19 (Figure 8) by replacing it with conventional spring means 50, secured to the edges of sheet-type membranes 51 by clamps 52. It will be understood that the several speakers illustrated and described herein can be modified in many other respects. The invention disclosed herein is therefore claimed as follows:

I claim:

1. Loud-speaker apparatus for reproducing sound with high fidelity and for maintaining such fidelity for a long time, said apparatus comprising: a pair of electrostatic loud-speakers, each of single-ended construction, each comprising a slightly arcuate, almost flat, electrically conductive plate, a series of membrane spacers extending generally along the convex surface of said plate, and electrically conductive membrane means insulated from said plate and tensioned over said spacers so that the membrane means generally follows the slight arcuate curvature of said plate; means mounting the speakers of said pair in spaced relation, facing one another, and closely air coupled to eliminate second harmonics; and electrical conductors, individually connected to the conductive plates and membranes of said pair of loud-speakers, for driving the entire membrane areas of both speakers in push-pull.

2. In apparatus as described in claim 1 the feature that said mounting means consists of a frame of insulating material, said plates being held in such frame by means including the membrane means.

3. In apparatus as described in claim 1, the feature that said electrical conductors are connected individually to said plates and to said membrane means in such a way as to drive the membrane means in push-pull at frequencies within a predetermined audio range; said mounting means having said plates, with said membrane means, mounted thereon with close acoustic air coupling therebetween as to all audible second harmonics of sound of said predetermined audio range.

4. In an electro-acoustic transducer, a pair of electrically conductive, substantially rigid, slightly arcuately curved backplates; a pair of groups of parallel membrane spacers, one group extending along the convex side of each of said backplates; a pair of thin, electrically conductive membrane sections, one tensioned over said spacers of each backplate in such a way that the section generally follows the curvature of said convex side; mounting structure, having said pair of backplates 50 mounted thereon, one opposite the other, with said membrane sections thereon and with a narrow, substantially unobstructed air space therebetween; and electrical conductors, separately connected to said backplates and membrane sections for feeding electrostatic signals to the entire area of each backplate and to the entire area of each membrane section and for thereby electrostatically vibrating the membrane sections on the spacers in push-pull, whereby the transducer is capable of such acoustic fidelity as is provided by electrostatic push-pull speakers and of such maintenance of acoustic performance as is provided by single-ended electrostatic speakers.
